UNITED STATES PATENT OFFICE.

JOSEPH DUKE HARRISON, OF BROOKLYN, NEW YORK.

FIREPROOF CONCRETE FLOOR CONSTRUCTION.

No. 913,820.

Specification of Letters Patent. Patented March 2, 1909.

Application filed January 30, 1908. Serial No. 413,341.

To all whom it may concern:

Be it known that I, JOSEPH DUKE HARRISON, a citizen of the United States, and a resident of Brooklyn, in the county of Kings and State of New York, have invented certain new and useful Improvements in Fireproof Concrete Floor Constructions, of which the following is a specification.

The invention relates to an improved system in fire-proof concrete unit floor construction, and consists in the novel features and structure hereinafter described, and particularly pointed out in the claims.

The object of my invention is to provide an improved and highly efficient fire-proof concrete unit floor construction possessing great strength and composed of parts of special character capable of being readily manufactured and conveniently and quickly placed in position without the use of temporary wood or metal centerings.

In accordance with my invention the possibility of misplaced reinforcement or the improper mixing of the concrete material is reduced to a minimum, and the uniform strength of the finished floor is assured.

The invention will be fully understood from the detailed description hereinafter presented, reference being had to the accompanying drawings, in which:

Figure 1 is a sectional perspective view, partly broken away and with a part of the concrete filling omitted, of a portion of a floor structure embodying my invention; Fig. 2 is a vertical transverse section of the same, the filling material at one side of the I-beam being omitted and the ceiling represented; Fig. 3 is a like view of a portion of a floor structure embracing features of my invention but in which the skew-backs, unlike the system shown in Figs. 1 and 2, do not extend below to afford soffit protection for the I-beams; Fig. 4 is a vertical section of the same on the dotted line 4—4 of Fig. 3; Fig. 5 is an enlarged detached transverse section through one of the unit slabs employed in the floor construction; Fig. 6 is a perspective view of the same; and Fig. 7 is an enlarged vertical section through one of the skew-backs on the dotted line 7—7 of Fig. 8, which is a perspective view of the same.

The novel features of the floor structure of my invention are the skew-backs 10 and slabs 11, these parts being separately and completely formed and assembled in the

manner shown in Figs. 1 and 2. In constructing the floor the skew-backs 10 are applied to the usual I-beams 14 and the slabs 11 are supported upon the skew-backs, the latter with the slabs forming flat arches between the beams. The skew-backs are hollow and the slabs when in position present hollows between their members, and in constructing the floor the skew-backs and the hollows presented by the slabs are filled with a concrete mixture 15 which will extend to the top level of the I-beams, as denoted at the left hand side of Figs. 1, 2 and 3. Upon the filling 15 are placed the usual sleepers 16 to which the board flooring 17 may be nailed in the customary manner. Between the sleepers 16 a cheap grade of material 18 is provided to fill the space between the concrete filling 15 and board flooring 17.

The skew-backs 10 will preferably correspond in width with the slabs 11 they are to support, and the preferred construction of the skew-backs and slabs is that shown in Figs. 5, 6, 7 and 8. The skew-back 10 is in the form of a hollow integral frame open at its top and at one side and closed at its bottom by the member 19, at its ends by the members 20 and at its outer side by the diverging members 21, 22, the member 21 extending downwardly and outwardly and the member 22 downwardly and inwardly. Each skew-back will preferably be formed with a vertical partition 23 located midway between and corresponding in outline with the end members 20. When the adjoining skew-backs at opposite sides of the beam 14 are, with their filling, intended to protect the lower flange of said beam in the manner shown in Fig. 1, their end members 20 and partitions 23 will be recessed, as at 24, to pass upon, and meet at their lower portions, centrally below the said flange. The skew-backs 10 are formed of reinforced concrete, the metal being indicated at 25 and preferably being in the form of a mesh frame extending through all the members or parts of the skew-back.

In the end members 20 and partitions 23 of the skew-backs 10 I preferably form apertures 26 to receive the lower ends of wires or hooks 27 by which the skew-backs may be suspended from the tops of the I-beams and thereby conveniently held in position against said beams preparatory to the assembling of the other parts of the floor structure.

The skew-backs being hollow and open at their upper ends may be conveniently filled, when in position, with concrete 15, and when so filled said skew-backs form solid 5 seats or bearings for the ends of the slabs 11 and also solid protection around the steel beams below their upper flanges.

The slabs 11 are of elongated form and at 10 their ends are inclined to firmly seat upon the upper inclined members 21 of the skew-backs. The slabs 11 are formed of reinforced concrete, the metal, indicated at 28, being in the form of a mesh of the general 15 outline of the slab and the concrete being molded on the same. I preferably form each slab 11 of two corresponding integrally connected members 29, 30, each comprising a top 31, downwardly diverging sides 32 and lower edge flanges 33, as more clearly shown 20 in Figs. 5 and 6, and said members being integrally connected at their adjoining lower edges and also by a suitable number of transverse members or partitions 34. Between the members 29, 30 of each slab is 25 formed a hollow or elongated chamber 35 to receive concrete filling 15, and between the adjacent sides of the slabs when the latter are assembled are created hollows or elongated chambers, corresponding with the 30 hollows 35, to receive the filling material 15. When the slabs 11 are assembled with their ends seated on the skew-backs their lower adjoining side edges and the adjoining side edges of the members or partitions 34 meet and thereby a continuous firm 35 floor structure of slabs 11 is formed. In addition to the reinforcing mesh 28, each slab contains upper and lower transverse metal rods 36 extending through the slabs and 40 their partitions 34, and also longitudinal tension rods 37 extending lengthwise through the slabs at the lower ends of the sides 32 and preferably below the lower transverse rods 36.

45 The slabs 11 are preferably formed throughout their length with transverse exterior ribs 38 which when the slabs are covered over by the filling 15, constitute keys which serve to thoroughly unite the 50 filling with the slabs. The form of the slabs 11, with their downwardly diverging sides and filling 15 covering them, is of importance in that the floor structure is enabled to contain a maximum amount of concrete 55 to meet the compressive stresses and a minimum amount where tensile stresses occur. The design of the slabs 11 also provides for the use of a minimum amount of metal reinforcement where compressive stresses occur 60 and a maximum amount to meet the tensile stresses.

Since the skew-backs and slabs are of shell or frame construction they require for their manufacture a comparatively small amount 65 of concrete material and hence they admit

of the use in their formation of a maximum strength mixture of a fire-proof concrete composed of cement and ground hard-burned clay or other fire resisting material. The filling 15 will be of concrete varying in quality of mixture or materials in accordance with the strength of floor required. The slabs and skew-backs will be of suitable size and their reinforcement of proper character to meet the requirements, and said slabs and 70 skew-backs are of such form and construction that their strength when in place, without the concrete filling, is sufficient to hold the weight the finished floor is designed to carry. The skew-backs will preferably be 80 constructed as shown in Figs. 1, 2 and 8, so as to afford soffit protection for the beams 14, but may be constructed, with less advantage, to rest upon the lower flanges of said beams, as shown in Figs. 3 and 4. 85

The method of assembling the parts of the floor structure will be understood without extended detailed explanation. The skew-backs 10 are supported by the beams 14 and the slabs 11 are seated upon the skew-backs 90 and form flat arches between the beams. The skew-backs and the hollows presented by the slabs are filled with the concrete 15, which covers the upper surfaces of said skew-backs and slabs. The I-beams 14 will 95 be connected by tie-rods 40 as usual, and the edges of the skew-backs and partitions 34 of the floor-slabs will be recessed, as shown in Fig. 1, to accommodate these rods.

I do not confine the invention in every 100 instance to slabs made double or of two members 29, 30, since said members may each constitute an individual slab, nor do I confine the skew-backs to a width adapting each of them to receive the double slab 105 shown, but the preferred and most efficient and economical embodiment of the invention is that presented in Figs. 1, 2, 6 and 8.

The advantages of the unit floor structure of my invention will be appreciated from 110 the foregoing description. I may however direct attention to the strength and efficiency of and convenience in assembling the unit members of the structure, the fact that in the manufacture of the skew-backs and 115 slabs the possibility of misplaced reinforcement is reduced to a minimum, the uniform strength of the floor structure as a whole, and the fact that no material other than that which constitutes a part of the finished floor 120 is necessary at the building, the cost and labor incident to constructing and removing temporary wood or metal centerings and the inconvenience of their presence in a building being eliminated. 125

What I claim as my invention and desire to secure by Letters Patent, is:

1. A floor structure comprising reinforced concrete slabs forming arches, said slabs being in the form of elongated hollow frames 130

comprising integral members each having a top, downwardly extending sides, laterally extending lower edge flanges and transverse partition members which meet at their edges when the slabs are assembled; substantially as set forth.

2. A floor structure comprising reinforced concrete slabs forming arches, said slabs being in the form of elongated hollow frames comprising integral members each having a top, downwardly extending sides, laterally extending lower edge flanges and transverse partition members which meet at their edges when the slabs are assembled, and said slabs having rods extending transversely through said partition members and tension rods extending longitudinally at the lower ends of said sides; substantially as set forth.

3. A floor structure comprising reinforced concrete slabs forming arches, said slabs presenting hollow frames each having a top, downwardly extending sides and transverse partition members which meet at their edges when the slabs are assembled, and said partition members having transverse rods extending through them; substantially as set forth.

4. A floor structure comprising reinforced concrete slabs forming arches, said slabs presenting hollow frames each having a top, downwardly extending sides and transverse partition members which meet at their edges when the slabs are assembled, and said partition members having transverse rods extending through their upper and lower portions; substantially as set forth.

5. A floor structure comprising reinforced concrete slabs forming arches, said slabs presenting hollow frames each having a top, downwardly extending sides and transverse partition members which meet at their edges when the slabs are assembled, and said partition members having transverse rods extending through them and said frames longitudi-

nal tension rods at the lower ends of said sides; substantially as set forth.

6. A floor structure comprising reinforced concrete slabs forming arches, said slabs presenting hollow frames each having a top, downwardly diverging sides, lower edge flanges and transverse partition members which meet at their end edges when the slabs are assembled, with transverse rods extending through said partition members; substantially as set forth.

7. A floor structure comprising reinforced concrete slabs forming arches, said slabs presenting hollow frames each having a top, downwardly diverging sides, lower edge flanges and transverse partition members which meet at their end edges when the slabs are assembled, with transverse rods extending through said partition members and longitudinal tension rods at the lower ends of said sides; substantially as set forth.

8. A floor structure comprising skew-backs having downwardly and outwardly inclined outer faces, and straight reinforced concrete slabs having downwardly and inwardly inclined ends conforming to and seated on said faces, said slabs forming arches and presenting hollow frames each having a top, downwardly extending sides and transverse partition members which meet at their edges when the slabs are assembled, and said partition members having transverse rods extending through them and said frames straight longitudinal tension rods at the lower ends of said sides; substantially as set forth.

Signed at New York city, in the county of New York, and State of New York, this 29th day of January A. D. 1908.

JOSEPH DUKE HARRISON.
